UNITED STATES PATENT OFFICE.

SIDNEY ALEXANDER KELLER, OF WOODMERE, NEW YORK.

DESIGN FOR A METAL-WORKER'S STOCK.

46,477.

Specification for Design.

Patented Sept. 29, 1914.

Application filed August 5, 1914. Serial No. 855,330. Term of patent 3½ years.

To all whom it may concern:

Be it known that I, SIDNEY A. KELLER, a citizen of the United States, and a resident of Woodmere, in the county of Nassau and State of New York, have invented a certain new, original, and ornamental Design for a Metal-Worker's Stock, of which the following is a specification.

The accompanying drawing is a view in

elevation of my newly designed metal-workers' stock.

I claim:

The ornamental design for metal-workers' stock, substantially as shown.

SIDNEY ALEXANDER KELLER.

Witnesses:

MAX SROLOVITZ,
F. DREYFUSS.
